UNITED STATES PATENT OFFICE.

JOHN YOUNG, OF NEWARK, NEW JERSEY.

DASH-POT FOR STEAM-ENGINES.

SPECIFICATION forming part of Letters Patent No. 337,644, dated March 9, 1886.

Application filed December 21, 1885. Serial No. 186,293. (No model.)

To all whom it may concern:

Be it known that I, JOHN YOUNG, of Newark, Essex county, in the State of New Jersey, have invented a certain new and useful Improvement 5 in Dash-Pots for Steam-Engines, of which the following is a specification.

I employ the term "dash-pot" to indicate the device—one for each steam-valve—which, when the valve is liberated, first acts to promptly effect the closing and then to gently arrest the closing motion. I have devised important improvements in the construction. I make the dash-pot annular, with the central portion the highest. The piston is guided on a 15 smoothly-turned central post. I provide means for maintaining a nearly perfect vacuum over this central post. The annular chamber which surrounds the base of this post imprisons a quantity of air, which resists the 20 descent of the piston near the bottom and gently arrests the motion. I attach particular importance to provisions for allowing the air to escape downward from this chamber into another conveniently arranged below. On the 25 rising of the piston with the opening of the valve, air is drawn upward again from the said lower chamber. I provide for taking the air downward from and delivering it to the chamber at two or more different levels and 30 for adjustably contracting the effective area of these openings. The interior of the cylinder which incloses the base of the piston is formed with an offset, as is common in this class of devices, allowing the air to flow out and the 35 piston to descend freely during the first part of the closing movement. Below this offset I bore conically, so that as the piston descends the air below is at first imprisoned only partly, the tightness of the fit increasing as the piston 40 descends. I provide means for introducing oil to the vacuum-chamber on the top of the central post, and for entirely excluding the air after each supply. The reservoir of oil thus provided insures efficient lubrication. 45 It will now be understood that at each opening of the valve the piston, in the form of an inverted cap with cylindrical sides and a sufficiently broad bottom rim, is drawn up forcibly, making a vacuum under the high central 50 portion, which remains unbroken during the whole movement. Under the rim of the piston

no vacuum is formed at any period, because the air can enter with tolerable freedom through the contracted passages from below during all portion of the rising movement, and as soon as the piston rises well into the conical portion of the bore and at all the later stages of the opening movement the air is admitted freely from above. On the liberation of the valve my piston descends rapidly and 55 is arrested gently. The sounds produced by the drawing in and forcing out of the air through the contracted passages in the lower portion are smothered by its communication with the chamber below instead of into the 60 open air. This makes the operation silent. I interpose leather in the vacuum-chamber in the center, and also in the annular arresting-chamber, to soften the concussion, when from any cause the descent is not otherwise suffi- 65 ciently arrested. I allow the piston to turn around freely on the central post. This promotes its wearing uniformly. A circular groove in the bottom of the annular arresting-chamber puts all portions in free communica- 70 tion with the one or more contracted passages through which this chamber communicates with the chamber below. The central post is hollow, and, by the aid of a valve mounted in the upper portion, delivers downward the con- 75 tents of the central or vacuum chamber at each descent of the piston. All the parts are easy of access for examination or repairs. 80

The accompanying drawings form a part of this specification, and represent what I consider the best means of carrying out the invention. 85

Figure 1 is a vertical central section. Fig. 2 is a plan view. Fig. 3 is a corresponding view of the central portion with the piston removed. Fig. 4 is a horizontal section on the line $\alpha\alpha$ in Fig. 1. 90

Similar letters of reference indicate corresponding parts in all the figures where they occur. 95

It will be understood that in my dash-pot, as in others, the piston is lifted and liberated at variable periods, according to the point at which the steam is to be cut off. On being liberated, it descends rapidly, and at the termination of the downward movement is arrested gently. 100

A designates the fixed portion of the apparatus. I will use additional marks, as A', when necessary to indicate special parts thereof.

A' is a portion of the bed-plate of the engine.
5 (Not represented.)

A² is the base-plate, faced upon A', and held firmly down by suitable bolts inserted through lugs A³. (See Fig. 2.) In its upper face is a circular groove, a². A passage, m, leads down 10 from this groove into a chamber below.

A⁴ is what I term the "post," a hollow cylindrical casting, formed in one with A², finished on its exterior, and grooved horizontally, as indicated by a⁴. The whole is inclosed in a 15 deep rim or hollow cylinder, A⁵ A⁶. The lower portion, A⁵, is bored cylindrically for a little distance up from the base, and tapering above. At a⁵ is an offset, the interior space being considerably enlarged at this level. Above this 20 offset the rim A⁶ extends upward further. The annular space between the post A⁴ and the rim A⁵ A⁶ is open at the top. A passage, n, (see Fig. 1,) is drilled or otherwise produced in the position represented. It is controlled 25 by an adjustable screw-plug, N. The passage m is controlled by an adjustable screw-plug, M.

B is the piston, certain portions being designated when necessary by additional marks, as B' B².

30 B' is a cylindrically-bored portion fitting closely around the post A⁴, and free to move up and down and also to turn around thereon.

B² is a stout bottom flange, and B³ the top, provided with a screw-threaded neck, spherically bored.

35 C is a spherically-bored cap, having an octagonal exterior and a screw-threaded interior, with a properly-shaped aperture in the top to allow vibration to the operating-rod D, which 40 is formed with a spherical lower end, D', and is properly connected at the upper end to the valve-operating mechanism. (Not represented.)

45 E is a removable casing tapped into the top of the post A⁴, and forming a seat for an automatic valve, G, mounted within and held up gently to its seat by a coiled spring, H, which latter abuts on the removable plug E', fitted in the base of E. There is a vertical winged space 50 around the valve H. The upper end of the casing E is hexagonal. When the rod D is disconnected and the piston is lifted off, the casing E may be conveniently inserted and removed by applying an ordinary wrench.

55 I is an annular piece of sole-leather secured by screws i on the top of the post A⁴.

J is an annular piece of sole-leather secured by screws j on the lower face of the flange B².

50 A screw-plug, P, serves to tightly close an orifice through which a small quantity of oil should be introduced at short intervals.

55 Operation: At each opening of the steam-valve (not represented) the piston is forcibly raised, thereby forming a cylindrical chamber over the post A⁴, and an annular chamber under the flange B². In the top chamber is, at each elevation of the piston, a nearly perfect

vacuum. The annular chamber under the flange B² is always filled with air, the air being drawn in at the commencement through 70 the apertures m and n, and at a later stage in the rising motion of the piston flowing freely in from above, as will be obvious. The pressure of the external atmosphere over the top chamber contributes with gravity to induce 75 a prompt descent of the piston so soon as it is liberated. As the piston descends, it commences to imprison the air under it. In the last part of the descending motion, after the lower edge of the piston has traversed the tapering part of A⁵ and reached the cylindrical portion, the only escape for the air below is through the passages m and n. The plugs M and N should be set so as to open these 80 passages just sufficiently to allow the valve to 85 close rapidly, but without concussion. Sound is produced by the rapid movement of the air through the passages m and n; but my arrangement insures that this is so effectually confined to the bottom chamber, a, that it is in- 90 appreciable in the engine-room.

The leathers I and J perform an important function. It will often occur in practice that in the effort to adjust the screw-plugs M and N to allow the valve to shut very promptly 95 the piston will not be quite enough cushioned, and will strike on the bottom. The leathers insure that such contact will never be metal with metal, but always through the interposition of these leathers. So soon as the concussion attracts attention, one or both the screws M and N should be set in a little, so as to retard the escape of air from under the piston a little more. Concussion will thus be removed.

100 I have shown four horizontal grooves, a⁴, extending around the post A⁴. There may be one or a series of such grooves, one above another. Their function is to form pockets, which have the effect to retard the flow of air 110 or oil through the joint, which is necessarily easy between the post A⁴ and the interior of the piston B. One alone may serve.

115 The vacuum-chamber over the center post is marked x, the annular cushioning-chamber under the flange B² is marked y, and the bottom chamber, which receives the blasts of air through the orifices m and n at each descent and suppresses the sound, is marked z.

120 The groove a², turned or otherwise produced in the upper face of A², insures a free communication from all parts of the cushioning-chamber to the orifice m, even when the piston is quite down.

125 Further modifications may be made. The proportions of the parts may be changed. The post A⁴ may be more or less high. I can vary the form of the controlling means M and N, which adjust the area of the passages for the flow of the air from the annular chamber under the piston into the bottom chamber at each descent.

130 Parts of the apparatus may be used without the whole. I can dispense with the upper por-

tion of the rim A⁶. The effect of this portion of the apparatus is mainly to protect the interior parts from injury from the introduction of hard substances or other cause when the 5 piston is raised.

I claim as my invention—

1. The post A⁴, made hollow, as shown, in combination with the valve G, mounted in the interior near the top, a spring, H, and piston 10 B, adapted to form a tight vacuum-chamber over the post, and an annular cushioning-chamber or dash-pot around the bottom, as herein specified.
2. The post A⁴, piston B, and cylinder A⁶ 15 A⁶, tapered below the offset, and arranged for joint operation as herein specified.
3. The piston B, cap C, and rod D, with its spherical end D', in combination with each other and with the post A⁴, valve G, and cylinder A⁶, arranged for joint operation as herein specified.
4. In a dash-pot, the bottom chamber, z, and

passage m between the same and the cushioning-chamber y, in combination with the piston B and operating means D, arranged to serve 25 as herein specified.

5. The duplicate passages m n and controlling means M N, leading from different levels in the dash-pot, communicating with the same bottom chamber, and arranged to serve as herein specified. 30

6. In a dash-pot, in combination with the rim A⁶, piston B, operating means D, hollow post A⁴, valve G, and spring H, the removable casing E, adapted to serve as herein specified. 35

In testimony whereof I have hereunto set my hand, at New York city, New York, this 19th day of December, 1885, in the presence of two subscribing witnesses.

JOHN YOUNG.
